CLAIM

The ornamental design for a handpiece, as shown and described.

DESCRIPTION

FIG. 1 is a front bottom perspective view of a handpiece embodying our new design;

FIG. 2 is a right side view thereof;

FIG. 3 is a left view thereof;

FIG. 4 is a top view thereof;

FIG. 5 is a bottom view thereof;

FIG. 6 is a back view thereof;

FIG. 7 is a front view thereof; and,

FIG. 8 is a front top perspective view thereof.

The broken line showing of access plates is for the purpose of illustrating environmental structure and forms no part of the claimed design.
